Application October 30, 1940, Serial No. 363,441
In Germany June 6, 1939

14 Claims. (CL 77—61)

This invention relates to a boring machine or a drill and refers more particularly to a boring machine capable of working upon the bottom surfaces as well as the side surfaces of bores in work pieces.

An object of the present invention is the provision of a boring machine of this type, the drive of which is so constructed that all the operations required for the drilling of a bore hole which is closed at one end take place entirely automatically.

Another object is the provision of steering and switching means enabling a boring machine to perform automatically all the boring operations necessary during the boring of a bore hole which is closed at one end.

A further object is the provision of an automatically operable boring machine capable of drilling a bore hole having a roof-like bottom surface.

Other objects will become apparent in the course of the following specification.

The drill of a boring machine of the described type should be capable of carrying out two different feed movements, namely, a longitudinal feed movement and a transverse feed movement. In accomplishing the objects of the present invention it was found desirable to provide a common steering device for actuating the means causing the two feed movements. Furthermore, in accordance with the present invention, the longitudinal feed movement is provided by the main drive of the machine which rotates the drilling tool. The common steering device influences the operation of the main driving motor. A separate drive which is influenced by the common steering device is provided for the transverse feed movement.

In accordance with the present invention, the steering device causes by mechanical means the longitudinal feed movement of the tool, while it provides for the transverse feed movement by electrical switching means.

The invention will appear more clearly from the following detailed description when taken in connection with the accompanying drawings showing, by way of example, a preferred embodiment of the inventive idea, namely, a boring machine aggregate used for providing compression chambers within cylinder heads of internal combustion engines.

A boring machine capable of drilling such compression chambers must be able to provide the roof-like bottom surfaces of these chambers. This roof-like bottom surface should not extend uniformly on both sides of its ridge, but must be

comprised of inclined surfaces one of which has a lesser angle of inclination than the other one.

In the drawings:

Figure 1 is a longitudinal section through a boring machine constructed in accordance with the principles of the present invention.

Figure 2 is a longitudinal section through the boring machine taken at right angles to the section of Figure 1.

10 Figures 1 and 2 show the position at the end of the transverse feed movement and shortly before the beginning of the quick return movement.

Figure 3 is a diagram illustrating the electrical 15 connections of the boring machine and also showing a single aggregate consisting of three boring machines operating simultaneously upon three cylinder head bore-holes formed one next to the other in a work-piece. Figure 3 illustrates the 20 position at the beginning of the longitudinal feed movement.

Figure 3a is similar to Figure 3 and illustrates the position at the beginning of the transverse feed movement.

23 Figure 3b is similar to Figure 3 and illustrates the position at the beginning of the quick return movement.

Figure 4 is a section along the line IV—IV of Fig. 3.

30 Figure 5 is a perspective view, partly in section, illustrating a work piece.

As shown in Figure 3, the aggregate has three boring machines A, B and C.

The boring machine A shown in Figures 1 and 35 2, has a tubular casing 1. The device operating the transverse feed of the tool 3 is situated in that part of the casing 1 which is close to the work piece W while the device producing the longitudinal feed movement of the tool 3 is situated 40 at the opposite end of the casing 1.

The drilling tool 3 is rotated by the main motor 45 (Fig. 3), the shaft 50 of which carries a pulley 51. And endless belt 52 passes over the pulley 51 and over the pulley 2 situated within 45 the casing 1 and illustrated in Figures 1 and 2.

The steel tool 3 is held within a tool holder 53 which is integral with one end of a swinging lever 4. The lever 4 is pivoted at 54 intermediate its ends in a sleeve or tube 5. The steel holder 53 is 50 enclosed by a support 55 having a round surface which is slidable upon inner supporting surfaces of the casing 1.

The inner free end of the lever 4 carries a roller 6 engaging a spatial cam 9, the form of which determines longitudinally as well as transversely

the form of the roof-like bottom surface 56 of the bore-hole 57.

The tube 5 encloses the lever 4 and constitutes a support for the tool 3. A spring 6 is situated between the tube 5 and an outer tube 7, so that the tube 5 rests by means of the spring 6 upon the tube 7 which transmits the pressure of the spring 6 to the casing 1. At the same time, the spring 6 maintains the roller 8 in contact with the surfaces of the cam 9.

When the steel 3 is brought to bear against the work piece W, the cam 9, due to its form, steers the reciprocatory longitudinal movement of the lever 4, the extent of this movement determining the height of the side surfaces of the bore hole.

The cam 9 is mounted upon a rod 10 which is movable longitudinally within the casing 1 but which cannot rotate relatively thereto. The rod 10 carries a pin 11 extending transversely through the rod 10 and carrying a roller 12. The roller 12 is situated within an annular groove 13 provided in a hollow steering element or drum 14 which is rotatably mounted within the casing 1.

The pulley 2 is rigidly connected with a gear wheel 15 the teeth of which mesh with the teeth of a pinion 16 mounted upon a shaft 17. The shaft 17 is rotatably mounted in the casing 1 and carries a worm 18 which meshes with a worm gear 19.

The worm gear 19 is firmly connected with a worm 20 which meshes with the worm-gear 21. The worm-gear 21 is firmly connected with the drum 14. Thus the rotation of the pulley 2 is transmitted to the drum 14.

The guide groove 13 of the drum 14 has an upwardly extending portion 13a (Fig. 2) which is used to provide the forward feed movement. The groove 13 also has a portion 13b extending parallel to the planing surface, and the roller 12 runs through this part of the groove without effect during the transverse feed. Finally, the groove 13 includes a downwardly extending portion 13c which is situated next to the portion 13a and which causes the return movement of the tool 3.

The gears 15, 16, 18, 19, 20 and 21 situated between the pulley 2 and the drum 14 have transmission ratios which are so selected with a view to the required form of the roof-like bore hole that the drum 14 carries out one revolution during the entire boring operation.

The pulley 2 drives the tube 7 so that the latter rotates along with the pulley 2. The tube 7 carries elongated pins 22 which project into corresponding bore-holes provided in the tube 5. Thus, the tube 5 rotates along with the tube 7 while it is capable of longitudinal motion relatively to the tube 7.

The tube 5 carries a shaft 23 and a gear wheel 24 is keyed upon the shaft 23. The gear wheel 24 meshes with the inner teeth 25a of a driving element or a worm gear 25.

The shaft 23 also carries a worm 26 which meshes with a worm gear 27 connected with a worm 28. A worm gear 29 meshes with the worm 28 and is connected with a worm 30. The worm 30 meshes with a toothed element 31 which is firmly connected with the lever 4.

When the worm gear 25 does not move, the gear wheel 24 carries out a planetary movement while meshing with the inner teeth 25a of the gear 25. Then the worm 30 which moves the swinging lever 4, is actuated by the gears 25 to 29. Normally, the cutting speed would drop during the transverse feed movement, as the cutting end of the steel 3 approaches the central axis of the bore hole 57, if the speed of rotation remains the

same. In order to avoid this drawback, a contact 32 is provided which is in engagement with a contact ring 32a and, during the transverse feed movement, slides over a resistance 33 (Fig. 1) which is connected with the driving motor 45 (Fig. 3). This arrangement is substantially similar to that used in electric street cars. Due to the diminution of the operative resistance of the motor 45 caused by the movement of the contact 32 over the resistance 33 (Fig. 4), the number of revolutions of the motor 45 is gradually increased. This increase of the speed of rotation of the motor 45 compensates for the described speed drop so that actually the cutting speed of the tool 3 remains the same. The sliding contact 32 begins its movement upon the resistance body 33 when the motor 45 has its greatest resistance and terminates it when the resistance is a minimum, so that, when the machine is switched on again, the contact 32 bridges a small gap between two ends of conducting strips.

The change from the forward feed movement of the transverse feed movement is carried out by electrical and mechanical means, which include a drive for the worm gear 25. The worm gear 25 is firmly mounted upon a worm shaft 35 serving as a motor shaft for two electric motors 41 and 43 (Fig. 3). The motor 41 runs with a smaller number of revolutions than the motor 43 which rotates in the opposite direction and many times as quickly. The rotors of the two motors 41 and 43 are rigidly connected with the shaft 35.

A ring 36 (Fig. 1) is keyed upon the drum 14 so that it can be adjusted longitudinally. A cam 37 (Fig. 3) is provided in one part of the ring 36. A steering lever or switch 38 which may be pivoted upon the casing 1, is actuated by the cam 37.

The switch 38 is included in an electrical circuit which comprises a relay 40 operating a switch 58 and connected with a hand lever 39. The switch 58 is situated in the circuit of the motor 41, said circuit including the mains a and b, the wires g, f, e' and e and a relay 69.

The drum 14 carries another ring 42 provided with a cam 59 which is used to close a switch 60 connected by a wire g with a relay 61 which is adapted to actuate a switch 71 situated in the circuit of the motor 43, to rotate the shaft 35 in the reverse direction and with a greater speed than the motor 41, to effect a quick withdrawal of the tool 3 from the bore hole 57.

The drum 14 carries a third ring 44 which is provided with a cam 62 adapted to close a switch 63 connected to a relay 64 actuating a switch 68 which is situated in the circuit c, d and c' of the main driving motor 45. The relay 64 is also connected with the switch 58 through the relay 69 and wire e' and with the relay 61 through the wires r and s and the relay 70. The arrangement is such that when the switch 63 actuated by the cam 62 of the ring 44 is closed, the relays 64 and 70 are both energized so that the main motor 45 and the motor 43 are stopped at the same time.

The machine operates as follows:

When the lever 39 is switched on, the motor 41 is energized by current flowing from the mains a and b through the wires e and e', the electromagnet 69, and the wires f and g (Fig. 3). The coil of the relay 69 is energized and attracts the core 69a in a direction opposite to that of the arrow x. Since the core 69a is connected by insulation with the core 64a, the latter is moved out of the coil of the relay 64. At the time the lever 39 is switched on, the relay 64 remains energized, since the cam 62 closes the switch 63. However, since the relay

64 is weaker than the relay 69, its electromagnetic force is overcome by that of the relay 69. Then the motor 45 is energized by current flowing through the wire c, the contact ring 32a, the sliding contact 32, the resistance 33 and the wires c' and d.

The rotation of the main motor 45 is transmitted by its shaft 50 and the pulley 51 to the endless belt 52, embracing the pulley 2 of the machine A (Fig. 2). The gear wheel 15 rotates with the pulley 2 and turns the pinion 16. The rotation of the pinion 16 is transmitted by the shaft 17, the worm 18, the worm gear 19, the worm 20 and the worm gear 21 to the drum 14 which is firmly connected with the worm gear 21. Thus, the drum 14 rotates along with the pulley 2. However, the transmission ratios of the worm gears 19 and 21 and the worms 18 and 20 are so selected that the drum 14 will carry out one revolution during the entire boring operation.

Since the roller 12 is situated within the groove 13 of the drum 14, the rotation of the drum 14 will cause a longitudinal movement of the piston 10 and the cam 8 connected therewith while the roller 12 is situated in the inclined groove portions 13a and 13c.

Since the pulley 2 is firmly connected with the sleeve 7, the latter will rotate along with the pulley 2 and due to the provision of the pins 22, the tube 5 will be also rotated along with the lever 4 and the tool 3.

The shaft 23 is eccentrically mounted in the tube 5 so that it will rotate along with the latter.

The portion 13a of the groove 13 will move forward the piston 10, the sleeve 5 and the lever 4, so that the tool 3 will carry out its forward feed movement. Since the motor 41 is energized, it will rotate the shaft 35. The motor 41 and its power transmitting means are so constructed that the shaft 35 and the worm gear 25 carried thereby will rotate with a speed equal to that of the tubes 5 and 7. Consequently, the shaft 23 and the gear wheel 24 carried thereby will rotate with the same speed as the worm gear 25 the inner teeth 25a of which mesh with the gear wheel 24.

Thus, during the forward feed movement the worm gear 25 rotates along with the sleeve 5 and the pulley 2, and with the same number of revolutions, so that the gear wheel 24 cannot carry out its planetary movement along the inner teeth 25a of the gear worm 25. Therefore, the entire transverse feed drive 26 to 31 is then at a standstill.

Since the machine A is connected by endless belts 66 and 67 with the machines B and C, the drums 14 of the three machines begin their rotation at the same time. The drums 14, the cam discs 36, 42 and 44 and the contact 32 sliding between the contact ring 32a and the resistance 33 begin their rotation simultaneously and turn once during the entire operation.

At the end of the forward feed movement steered by the inclined groove 13a, namely, at the moment the roller 12 begins to be guided by the straight groove portion 13b, the cam 37 of the ring 26 closes the switch 38, thereby closing the circuit of the wires h, i, and k, switching off the switch 58 of the relay 40 and stopping the motor 41 along with the shaft 35 and the worm gear 25 carried thereby by interrupting the circuit of the wires e, e', f, and g (Fig. 3a).

As soon as the motor 41 is brought to a stop, the gear 24 of each machine begins to carry out its planetary movement while meshing with the inner teeth 25a of the worm gear 25. The worm gear 24 will actuate by means of the shaft 23, the worm

26, the worm gear 27, the worm 28, the worm gear 29, the worm 30, the toothed element 31 and the lever 4 which will swing about its pivot 54, while the spring 6 presses the roller 8 against the surfaces of the cam 9. Thus, the driving of the sleeves 7 of the three machines by the motor 45 causes a gradual swinging movement of the levers 4 to cause the tools 3 to carry out their transverse feed movement inwardly from their outer positions.

The oscillatory movements of the lever 4 are determined by the cam 9 and in the course of these movements, the cutting edges of the tools 3 can move in two planes necessary to permit it to shape the roof-like bottom surface 56 of the bore-hole 57.

While this transverse feed movement of each tool 3 is carried out by the swinging movement of the lever 4, the contact 32 assumed the position a' (Fig. 4) in contact with the resistance 33, and its further movement upon this resistance in the direction of the arrow y diminishes continually the amount of resistance electrically connected with the motor 45 in order to increase the rotation of the motor gradually while the edge of each tool 3 approaches the central axis of the bore hole, in order to maintain substantially uniform the cutting speed of the tool 3.

During the transverse feed movement the roller 12 is situated within the portion 13b of the groove 13.

The ring 42 is so arranged upon the drum 14 that its cam 59 closes the switch 60 as soon as the planing operation, i. e. the transverse feed movement, has been completed and the roller 12 begins to be guided by the groove 13c. The switch 60 operates the relay 61, closing the circuit of the motor 43, since the core 70a is withdrawn from the currentless coil of the relay 70 and is attracted along with the core 61a by the coil of the relay 61. The switch 70 connected with the core 61a closes the circuit consisting of the wires a, a' and b and the motor 43.

Since the motor 43 is so constructed that it rotates quicker than the motor 41 and in an opposite direction, it will actuate the shaft 35 and the gears 24 to 31, so that each lever 4 along with the tool 3 carried thereby will return quickly to their original position.

In the meantime, the steering drum 14 continues its rotation and the roller 12 is situated within the inclined part 13c of the groove 13. This will move the roller 12 along with the piston 10 in the direction away from the workpiece. Since the spring 6 presses against the tube 5, the tube 5 and the lever 4 carried thereby will move along with the piston 10, while the roller 8 remains in contact with the cam 9. Thus, the tools 3 are withdrawn from the bore holes 57. The sliding contact 32 leaves the windings of the resistance 33 and moves over a contact with the same maximum velocity (Fig. 4).

At the time when the roller 12 finds itself at the end of the inclined groove portion 13c, the piston 10 and the lever 4 are situated in their extreme withdrawn position, which is also their position at the beginning of the drilling operation.

The ring 44 which is provided with the cam 62, is so disposed upon the drum 14 that as soon as the return movement of the piston 10 is completed, the cam 62 closes the switch 63 which opens the contacts 66 and 71 through the wires m, m', n, s and r, and electromagnets 64 and 70 to switch off the main driving motor 45 and the auxiliary motor 43. Thus the machine is brought to a

stop. After the automatic stopping of the machine and just before the starting position of the new cycle shown in Figure 3, the positions of the cams 37, 59 and 62 are such that only the cam 62 is in position to close its associated contact 63, thereby acting to energize the relays 61 and 64 to open the switches 71 and 58, respectively.

In order to begin the operations, the operator must move the hand lever 39 from the inoperative position to the operative position shown in Figure 10. Then the motor 41, the relay 64 and the motor 45 are energized and the operations are repeated.

The machine is so constructed that a plurality of units may be conveniently combined into a single aggregate. As far as the drilling of the cylinder heads of a motor are concerned, the number of the machine units carrying out this operation should correspond to about one-half of the number of the cylinders.

In the arrangement shown in Figure 3, three 20 units A, B and C are operated simultaneously. The motor 45 drives the pulley 2 of the unit A by means of an endless belt 52. A belt transmission 66 transmits the drive from the unit A to the unit B, while the belt transmission 67 transmits the drive from the unit B to the unit C.

All the units A, B and C have a common worm shaft 35 which, at the same time, constitutes the driven shaft and the rotor-carrying shaft of the two motors 41 and 43.

It is apparent that the specific illustrations shown above have been given by way of illustration and not by way of limitation and that the structures above described are subject to wide variation and modification without departing from the scope or intent of the present invention; all of such variations and modifications are to be included within the scope of the present invention.

What is claimed is:

1. In a drill, a tool holder, means connected with said tool holder for causing the same to carry out a transverse feed movement, means connected with the first-mentioned means for rotating said tool holder, steering means actuated by the second-mentioned means and operatively connected with the first-mentioned means for causing the tool holder to carry out a longitudinal feed movement, a main motor driving the second-mentioned means, and means operatively connecting said main motor with the third-mentioned means.

2. In a drill, a tool holder, means connected with said tool holder for causing the same to carry out a transverse feed movement, means causing the tool holder to carry out a longitudinal feed movement, an electrical device connected with the first-mentioned means for actuating the same, a mechanical device connected with the second-mentioned means for actuating the same, and a common steering device connected with said electrical device and said mechanical device for actuating said devices.

3. In a drill, a tool holder, means connected with said tool holder for causing the same to carry out a transverse feed movement, a steering drum having a curved slot formed therein, movable means having an element engaging the first-mentioned means and another element in contact with said slot to impart a forward longitudinal feed movement and a longitudinal reverse movement to the first-mentioned means and the tool holder when said drum is rotated, means connected with the first-mentioned means and said tool holder, means operatively connecting the third-mentioned means with said drum for rotating the latter, and means

5 connected with the first-mentioned means for actuating the same, the slot in said drum being so formed that the second-mentioned means are moved only to effect a forward longitudinal feed movement and the longitudinal reverse movement.

4. In a drill, a tool holder, means connected with said tool holder for causing the same to carry out a transverse feed movement, a steering drum having a curved slot formed therein, reciprocable means having an element engaging the first-mentioned means and another element in contact with said slot to impart a longitudinal feed movement to the first-mentioned means and the tool holder when said drum is rotated, means connected with the first-mentioned means for rotating the first-mentioned means and the tool holder, means operatively connecting the third-mentioned means with said drum for causing said drum to carry out one revolution during an entire boring operation, and means connected with the first-mentioned means for actuating the same.

5. In a drill, a tool holder, a lever having one end carrying said tool holder, a longitudinally movable tube, means carried by said tube for pivotally supporting said lever within the tube, means connected with said lever for causing the same to carry out a transverse feed movement, means connected with said tube for rotating the same, whereby said lever and said tool holder are rotated, and means engaging the other end of said lever for causing said lever and said tool holder to carry out a longitudinal feed movement.

6. In a drill, a tool holder, a lever having one end carrying said tool holder, a longitudinally movable tube, means carried by said tube for pivotally supporting said lever within the tube, a cam having a surface corresponding in form to a surface of the bore hole to be drilled, said cam surface being engaged by the other end of said lever, resilient means engaging said tube to press said lever against said cam surface, means connected with said lever for swinging the same to cause said tool holder to carry out a transverse feed movement, means connected with said tube for rotating the same, whereby said lever and said tool holder are rotated, and means moving said cam longitudinally to cause said lever and said tool holder to carry out a longitudinal feed movement.

7. In a drill, a tool holder, a swinging lever having one end carrying said tool holder, an electric motor, means operatively connecting said motor with said lever to move said lever and cause said tool holder to carry out a transverse feed movement, a rotary steering element, means actuated by said steering element to cause said lever and said tool holder to carry out a longitudinal feed movement, cam rings carried by said steering element and rotatable therewith, and means contacting said cam rings and operatively connected with said motor for switching it on and off.

8. In a drill, a tool holder, a swinging lever having one end carrying said tool holder, an electric motor, means operatively connecting said motor with said lever to move said lever and cause said tool holder to carry out a transverse feed movement, a rotary steering element, means actuated by said steering element to cause said lever and said tool holder to carry out a forward feed movement, at least one cam ring carried by said steering element and rotatable therewith, and means contacting said cam ring and operatively connected with said motor to actuate the means carrying out the transverse feed movement after the completion of the forward feed movement.

9. In a drill, a tool holder, a lever having one end carrying said tool holder, a longitudinally movable tube, means carried by said tube for pivotally supporting said lever within the tube, means connected with said tube for rotating the same, whereby said lever and said tool holder are rotated, a rotary driving element, means operatively connecting said rotary driving element with said lever to cause said lever and the tool holder carried thereby to carry out a transverse feed movement when said rotary driving element is at a standstill and said tube is rotated, an electric motor, means operatively connecting said electric motor with said rotary driving element for rotating said rotary driving element with a speed equal to that of said tube, a rotary steering element, means actuated by said steering element to cause said lever and said tool holder to carry out a forward feed movement, at least one cam ring carried by said steering element and rotatable therewith, and means contacting said cam ring and operatively connected with said motor to stop the rotation of said rotary driving element as soon as the forward feed movement has been completed.

10. In a drill, a tool holder, a lever having one end carrying said tool holder, a longitudinally movable tube, means carried by said tube for pivotally supporting said lever within the tube, means connected with said tube for rotating the same, whereby said lever and said tool holder are rotated, a rotary shaft eccentrically mounted in said tube, means operatively connecting said rotary shaft with said lever to cause said lever and the tool holder carried thereby to carry out a transverse feed movement when said shaft is rotated, a gear wheel keyed upon said shaft, a worm gear meshing with said gear wheel, an electric motor, means operatively connecting said electric motor with said worm gear for rotating said worm gear, whereby said shaft does not rotate about its own axis when said worm gear is rotated, a rotary steering element, means actuated by said steering element to cause said lever and said tool holder to carry out a forward feed movement, at least one cam ring carried by said steering element and rotatable therewith, and means contacting said cam ring and operatively connected with said motor to stop the rotation of said worm gear as soon as the forward feed movement has been completed.

11. In a drill, a tool holder, a lever having one end carrying said tool holder, a longitudinally movable tube, means carried by said tube for pivotally supporting said lever within the tube, means connected with said tube for rotating the same, whereby said lever and said tool holder are rotated, a rotary driving element, means operatively connecting said rotary driving element with said lever to cause said lever and the tool holder carried thereby to carry out a transverse feed

movement when said rotary driving element is at a standstill and said tube is rotated, two electric motors rotatable with different speeds and in opposite directions, means operatively connecting said electric motors with said rotary driving element, a rotary steering element, means actuated by said steering element to cause said lever and said tool holder to carry out a forward feed movement and a reverse movement, cam rings carried by said steering element and rotatable therewith, and means contacting said cam rings and operatively connected with said motors for switching on the slower motor during the forward feed movement, for switching off both motors during the transverse feed movement and for switching on the faster motor during the reverse movement.

12. In a drill, a tool holder, means connected with said tool holder for causing the same to carry out a transverse feed movement, means connected with the first-mentioned means for rotating said tool holder, a steering device actuated by the second-mentioned means and operatively connected with the first-mentioned means for causing the tool holder to carry out a longitudinal feed movement, a main electrical motor driving the second-mentioned means, a resistance connected with said motor, and means connected with said steering device and varying said resistance during the transverse feed movement to increase gradually the speed of said motor.

13. In a drill, a tool holder, means connected with said tool holder for causing the same to carry out a transverse feed movement, means connected with the first-mentioned means for rotating said tool holder, steering means actuated by the second-mentioned means and operatively connected with the first-mentioned means for causing the tool holder to carry out a longitudinal feed movement, a main electrical motor driving the second-mentioned means, and means actuated by the third-mentioned means for switching off said motor after the completion of a drilling operation.

14. In combination, an aggregate comprising a plurality of drills, each of said drills comprising a tool holder, means connected with said tool holder for causing the same to carry out a transverse feed movement, means connected with the first-mentioned means for rotating said tool holder, and steering means actuated by the second-mentioned means and operatively connected with the first-mentioned means for causing the tool holder to carry out a longitudinal feed movement; said aggregate further comprising a single electric motor for rotating the tool holders of all the drills, and a single pair of electric motors connected with the means causing the transverse feed movement of the tool holders for actuating the same.

PAUL REGUL
